Primary Examiner — Doris Clark(74) *Attorney, Agent, or Firm* — Price Heneveld LLP(57) **CLAIM**

I claim the ornamental design for a faux window assembly, as shown and described.

DESCRIPTION

FIG. 1 is a perspective view showing a front, top and side of the faux window assembly;

FIG. 2 is a front elevational view of the faux window assembly;

FIG. 3 is a rear elevational view of the faux window assembly; FIG. 4 is an elevational view of a first side of the faux window assembly;

FIG. 5 is an elevational view of a second side of the faux window assembly;

FIG. 6 is a top plan view of the faux window assembly; and, FIG. 7 is a bottom plan view of the faux window assembly. The dashed lines and broken lines are for purposes of illustrating environmental structure and form no part of the claimed design.
